UNITED STATES PATENT OFFICE.

WILLIAM B. NICHOLS, OF DELAWARE CITY, DELAWARE.

DESIGN FOR A PHOTO-FRAME.

52,143.

Specification for Design.

Patented July 2, 1918.

Application filed April 25, 1918. Serial No. 230,809. Term of patent 7 years.

To all whom it may concern:

Be it known that I, WILLIAM B. NICHOLS, a citizen of the United States, residing at Delaware City, in the county of New Castle and State of Delaware, have invented a new, original, and ornamental Design for Photo-Frames, of which the following is a specification, reference being had to the accompanying drawing, forming part thereof.

In the drawing,

Fig. 2 is an edge view thereof.

I claim:

The ornamental design for a photo frame, as shown.

In testimony whereof I have signed my name to this specification.

WILLIAM B. NICHOLS.
